UNITED STATES PATENT OFFICE.

HERMAN H. MEYER, OF DAVENPORT, IOWA.

CONNECTING-ROD.

SPECIFICATION forming part of Letters Patent No. 364,536, dated June 7, 1887.

Application filed March 30, 1887. Serial No. 233,045. (No model.)

To all whom it may concern:

Be it known that I, HERMAN H. MEYER, a citizen of the United States, residing at Davenport, in the county of Scott and State of Iowa, have invented new and useful Improvements in Connecting-Rods for Steam-Engines, &c., of which the following is a specification.

My invention relates to connecting-rods for machinery generally, and particularly for steam-engines which have adjustable boxes.

The improvement consists in having interposed between the adjustable section of the box and the connecting-rod an interlocking key and wedge, the latter being of a width equal to the thickness of the rod, nearly as deep as the box, and having a tongue or projection depending from the lower edge and extending the remaining distance, so that the sum of the wedge and projection is equal in length to the depth of the box. The key is recessed, and the wedge is adapted to fit in said recess in such manner that a portion of the key overlaps the wedge at each end, and a movement thereof effects a corresponding movement of the wedge. The parts are so disposed that the wedge bears with its whole front surface against the box, and with its rear surface partly against the connecting-rod and partly against the key. In other words, the wedge has an equal bearing on its front and rear sides, which will more fully hereinafter appear from the description and drawings, in which—

Figure 1 represents in sectional side view the two ends of a connecting-rod, the boxes of each end having my improved key and wedge fastening as used with what is known as a "solid" and a "strap" rod. Fig. 2 shows in side view the solid end of a connecting-rod, the wedge and key receiving section of the box being removed and shown in Fig. 3. Fig. 4 shows in side view the strap end of a connecting-rod and the manner of putting the wedge in place upon the key. Fig. 5 shows in partial section the solid and strap end of a connecting-rod on the line xx of Fig. 1. Fig. 6 is a cross-section on the line yy of Fig. 5, showing the wedge in place. Fig. 7 shows the key in side view; Fig. 8, the wedge in side and face view, and Fig. 9 the wedge and key as they are placed when fastened in the rod upon the box.

Heretofore the box has been adjusted by a key which is driven up by set-screws. In such use of the key the box, which is of soft metal, is crushed in, and often forced out of shape by the great pressure exerted against it through the piston of the engine on account of the narrow surface of the key in contact with and bearing against the box. It then becomes necessary to put in either a liner between the box and key, or the box must be renewed, and in case that a steel plate is used between the box and key one or the other will get crushed in, whichever is made of the softest metal. If the key is dented, it becomes useless, as it cannot be driven up or down. If a wedge only is used, set-screws or bolts are necessary for adjusting it, which bolts cannot be adjusted while the engine is in motion, which is frequently required. A key can be moved while the engine is in motion or at rest, and the key adjustment is in this respect far preferable to all other modes and means of adjustment for the boxes of a pitman or connecting-rod.

The connecting-rod A may have either a solid end, provided with the usual opening, C, for the reception of the boxes, or the strap B secured thereto by suitable bolts for securing and holding the boxes. The adjustable section of the box a may be located at either end of the opening, and has its straight side inclined. The wedge D, placed against the box, is equal in width to the width of the connecting rod or strap, and in length to nearly the depth of the box, but sufficiently short to permit an adjustment. The projection d, extended from the lower edge of the wedge, is of a width equal to the thickness of the key, so as to enter the opening b, Figs. 4 and 6, in the lower side of the rod or strap. The combined length of the wedge and projection is equal to the depth of the box, so it can be slipped in sideways behind the box.

The key E is of ordinary length, to project above and below the rod, and is provided with the recess e, of a length equal to the depth of the box, or the combined length of the wedge and projection, and of a depth equal to the thickness of the wedge, so that the wedge will come flush with the key when fitted in the recess, and both bear against the box when adjustment takes place. The key passes through

openings *b* and *b'* in the strap, and is seated in a groove, *f*, in the rod, which groove is of a depth equal to the width of that portion of the key, *E'*, directly opposite to the recess, so that 5 when the key is seated in the groove the portion *E'* will come flush with the end of the rod against which the wedge rests.

In practice the end of the box may or may not be flanged, as desired, and the wedge 10 is fitted against the end of the box, preferably by slipping it in sidewise, and the key which is fitted in the groove *f* receives the wedge in its recess. The whole front surface of the wedge bears against the box, and the rear surface 15 rests against the end of the rod on each side of the groove and that portion *E'* of the key, as seen in Fig. 5.

In the event of the bearing becoming worn, the box can be adjusted by driving upon the 20 key, which, interlocking with the wedge, carries it down with it and forces the box up, so as to take up the wear. The projection *d* of the wedge enters the opening *b* and forms a 25 guide for the wedge, and holds the wedge in position in case the box has not end flanges.

I claim—

1. The combination, with the rod having a groove and the adjustable bearing, of the recessed key fitted in the groove, and the wedge seated in the recess of the key and interposed 30 between the rod and the bearing, substantially as described, for the purpose set forth.

2. The combination, with the rod and the adjustable bearing, of the wedge interposed between the rod and bearing, and having a projection extended from its lower edge, and the recessed key, substantially as set forth. 35

3. The combination of the rod, the adjustable bearing, the key, and the wedge interlocked with the key and of a width equal to 40 the width of said rod, and having an equal bearing surface on its front and rear sides, substantially as described, for the purpose specified.

In testimony wherof I have hereunto set my 45 hand in the presence of two subscribing witnesses.

HERMAN H. MEYER.
